(57) **CLAIM**

We claim the ornamental design for a metal spool for wire and the like, as shown and described.

DESCRIPTION

FIG. 1 is a perspective view of a metal spool for wire and the like in accordance with the present design;

FIG. 2 is an enlarged fragmentary view of the opening in FIG. 1;

FIG. 3 is a cross sectional view taken along line 3-3 of FIG. 1;

FIG. 4 is a perspective view of the metal spool for wire and the like of FIG. 1 as seen from the opposite side;

FIG. 5 is an enlarged fragmentary view of the opening in FIG. 4;

FIG. 6 is a perspective view of a first variant of the metal spool for wire and the like;

FIG. 7 is an enlarged fragmentary view of the opening in FIG. 6;

FIG. 8 is a cross sectional view taken along line 8-8 of FIG. 6;

FIG. 9 is a perspective view of the metal spool for wire and the like of FIG. 6 as seen from the opposite side; and,

FIG. 10 is an enlarged fragmentary view of the opening in FIG. 9.

The design is the visual features of the metal spool for wire and the like as shown in the drawings. The dash-dot-dash lines in the drawings depict environmental subject matter only and form no part of the claimed design. In addition, the broken lines used to identify enlarged fragmentary views form no part of the claimed design.

1 Claim, 4 Drawing Sheets
